UNITED STATES PATENT OFFICE

BENEDICT T. GIBBS, JR., OF CHICAGO, ILLINOIS, ASSIGNOR TO MORDEN FROG & CROSS-
ING WORKS, OF CHICAGO, ILLINOIS, A CORPORATION OF ILLINOIS

RAIL SUPPORT

Application filed April 15, 1929. Serial No. 355,053.

My present invention relates in general to rail supports and has more particular reference to an improved base plate for rail mounting and bracing.

5. An important object of my invention is to provide an improved base plate particularly adapted for use in connection with a rail brace used to rigidly brace a rail against side-wise movement, particularly at and adjacent to switch points whose lateral movements to and from the unsupported side of the rail render the use of spikes or similar fastening devices impractical.

Another important object of the invention 15 is to provide a one piece base plate having integral abutments for the rail to be supported and the rail brace and improved means for securing the brace to the plate.

Another important object of the invention 20 is to provide an embossed bolt receiving portion through which the bolt extends and which provides an increased bearing surface to prevent the bolt from turning when the clamp or brace is secured in place.

25. Among the other important objects of my invention are to provide a novel and improved means for and method of making my improved plate; to simplify the manufacture of rail plates; to improve the present method 30 of bracing rails and to reduce cost of installing and maintaining braced rails; and to produce a more rugged and satisfactory rail brace.

Numerous other objects of the invention 35 will be apparent as it is more fully understood from the following description which taken in connection with the accompanying drawings discloses a preferred embodiment of my invention.

40. Referring to the drawings:

Figure 1 is a plan view of a section of track, including a switch point showing how the plates of my invention are applied in supporting rails;

45. Figure 2 is a vertical cross section taken substantially along the line 2--2 of Figure 1;

Figure 3 is an enlarged view of a portion of the track shown in Figure 1, showing a rail and supporting and bracing devices of 50 my invention at the switch point;

Figures 4 and 5 are respectively top and fractional lower perspective views of a rail plate embodying my invention;

Figure 6 is a vertical section taken substantially along the line 6--6 in Figure 4. 55

To illustrate my invention I have shown on the drawings in Figure 1 a section of a track at a switch point and including the usual rail track ties 13 and shiftable point segments 15. The rails are supported from 60 and secured to the ties at and adjacent the switch point, by means of rail plates 17 of novel construction and arrangement and bracing means 19 which co-operate with the plate 17 to brace the rails and securely clamp them 65 to the plate. At other points removed from the switch point, the rails and point segments are carried on slide plates 21. The rail supporting plates 17 and 21 may be secured to the ties in any convenient or suitable manner as 70 by the usual spikes 23 which pass through perforations 25 formed in the plates.

The plate 17 as illustrated is a rectangular strip of material and may be made of any suitable material such for instance as 75 malleable iron which is tough and has good rust resisting qualities. The plate is provided with spike holes 25 at its ends and is offset at one end inwardly of the spike hole to provide a raised elongated slide bearing 80 surface 27 for carrying the movable point section 15. The offset portion is formed at one end to provide a straight rectangular shoulder 29 adapted to provide an abutment 85 for the inner edges 31 of the rail flange. 85

At the other end of the plate and inwardly of the spike holes 25, an upstanding ridge or fin 33 is formed across the upper surface of the plate and provides a face 35 opposing and spaced from the straight shoulder 29. 90 The shoulder 29 and the fin or ridge 33 provide abutments between which the rail may be clampingly held, the shoulder formed by the ridge or fin 33 serving as an abutment 95 for the bracing means 19.

The bracing means 19 includes a brace block 37 comprising a suitable casting formed to provide a wedge and clamp portion 39 adapted to fit between the base flange and head of the rail 11 and a flanged portion 100

41 extending outwardly of the base of the wedge portion, the wedge and flanged portions 39 and 41 being braced by suitable strengthening flanges 43. The outer edge of the flange 41 has an angular relationship with the face of the wedge portion 39 and is formed to co-operate with a suitable wedge portion 45, which engages between the outer edge of the flange 41 and the inner face 35 10 of the fin 33. The wedge 45 is provided with an upstanding overhanging portion 47 provided with a plurality of apertures 49 and corresponding holes are formed along the upper surfaces of the flange 41 and a pin 51 is provided to enter the apertures 49 and take into the sockets in the flange 41 to thereby retain the wedge in its assembled position. It will be apparent that by regulating the point to which the wedge is driven, the wedging effect of the member 37 may be controlled 20 to provide means for adjusting the rail clamp in order to compensate for wear of the parts.

In order to hold the clamp 37 securely to the plate, the flange 41 is provided inwardly 25 of its outer edge with a pair of longitudinal slots 53 through which the shank of a bolt may extend, the head 57 of the bolt 55 being countersunk in a suitable depression 59 formed in the under face of the plate 21. 30 The shank of the bolt 55 is squared at 61, or otherwise provided with a non-circular co-operating sectional configuration adjacent the head 57 of the bolt and the plate 21 is provided with a corresponding square or 35 other suitable non-circular aperture 63 through which the formed portion of the bolt may extend.

The plate also is provided with a boss 65 in its upper face at the aperture 63. The 40 upper end of the bolt shank extends through the slot 53 and carries a suitable retaining nut 67 threaded thereto above the flange 41, which bolt on being tightened clamps the rail flange between clamping member 37 and the plate 21. It will be apparent of course 45 that the slot 53 provide for the lateral movement of the clamp member 37 with respect to the bolts 55 when the former is tightened against the rail by the wedge member 45. It 50 is thought also that the advantage of providing a rail plate having a pronounced embossment 65 around the noncircular apertures whereby greater bearing surface for the bolts 55 at the point where they engage 55 the plate may be appreciated. Heretofore bolts have shown a tendency to strip their keyed connection in the non-circular aperture due to the deficiency in the bearing surface at the non-circular portion of the bolt 60 shank.

A further improvement and advantage resides in the provision of a rail plate having an integral switch point bearing surface 27, an integral abutment 33 for the wedge member 45 and having the embossment 65 formed

directly in the plate during the manufacturing operation.

It is thought that the invention and numerous of its attendant advantages will be understood from the foregoing description and it is obvious that numerous changes may be made in the form, construction and arrangement of the various parts without departing from the spirit and scope of the invention or sacrificing any of its material advantages, the form herein described being a preferred embodiment of the invention.

Having thus described my invention what I claim as new and desire to secure by Letters Patent is:

1. As an article of manufacture, a tie plate for tracks comprising a plate having an offset slide portion for supporting a movable rail of a switch point, and providing a shoulder at one end of the slide portion against which to clamp a stationary rail, an abutment spaced from said shoulder to hold a rail clamping device in operative position whereby to secure a rail to the shoulder and an off-set boss formed in said plate intermediate the rib and the shoulder, said boss having a non-circular aperture whereby to receive a co-operating fastening device, for securing the rail clamping device to the plate.

2. As an article of manufacture, a tie plate for tracks comprising means forming a shoulder in said plate against which to clamp a track rail, an integral abutment providing a bearing surface facing said shoulder to provide means for holding a rail clamp in operative position whereby to secure a rail against said shoulder and an offset boss formed in said plate intermediate the shoulder and the abutment, said boss portion of the plate being perforated and formed to support a non-rotatable fastening member in position to secure the clamping device to the plate.

3. As an article of manufacture, a tie plate for tracks comprising a plate and means to clampingly secure a track rail to said plate, said means including an integral shoulder providing an abutment against which to engage a rail clamping device and a boss formed in said plate in spaced relationship with the shoulder, said boss being perforated and formed to non-rotatably support a fastening member in position to engage and secure said rail clamping device to the plate.

4. As an article of manufacture, a tie plate for tracks comprising a plate having means providing an abutment against which to engage a rail clamping device and an off-set boss formed in said plate in spaced relationship with said abutment, said boss being perforated and formed to support a non-rotatable fastening member for use in attaching the rail clamping device to the plate.

5. As an article of manufacture, a tie plate for tracks comprising a plate having means providing an abutment against which to en-

5 gage a rail clamping device and an off-set boss formed in said plate in spaced relationship with said abutment, said boss having a non-circular perforation adapted to receive and support a non-rotatable fastening member having a corresponding non-circular cross section in position to secure the clamping device to the plate.

6. In combination, a tie plate for tracks 10 comprising a plate providing an off-set slide portion for carrying a movable rail of a switch point, a shoulder at one end of said slide portion against which to clamp a stationary rail, an abutment formed in said plate 15 in spaced relationship with the shoulder to form a bearing surface against which to engage a rail clamp, and an off-set perforated boss adapted to receive and support a fastening means whereby to secure the rail clamp to the plate, a rail carried by said plate with an 20 edge engaging said shoulder, a rail clamp mounted to the plate between said rail and said abutment, and a fastening member setting in said perforation and engaging said 25 rail clamp to secure the form firmly to the plate.

7. In combination, a tie plate for tracks comprising a plate having a shoulder formed therein against which to clamp a track rail, 30 an integral abutment spaced apart from said shoulder and an upwardly bossed portion provided with a non-circular socket adapted to support a fastening means for securing a clamping device to the plate, a rail carried 35 by the plate with one edge engaging said shoulder, a rail clamping device wedgingly mounted to the plate between the abutment and the rail whereby to clamp the latter against the shoulder and a fastening member having a non-circular portion seated in said 40 socket and extending to engage and secure the rail clamp to the plate.

8. In combination, a tie plate for tracks 45 comprising a plate for supporting a rail clamp and an off-set embossment formed therein in spaced relationship to the said abutment, said embossment having a non-circular socket for receiving and supporting a fastening device for securing a rail clamp to the plate of a rail mounted to said plate, a 50 rail clamp assembled wedgingly between said rail and said abutment and a fastening device having a non-circular portion seated in said socket and extending to engage and secure the rail clamp to the plate in rail clamping position.

9. In combination, a tie plate for tracks 55 comprising a formed plate for supporting a track rail and having an abutment providing engagement for a rail clamp and an integral off-set boss adjacent said abutment, said boss providing a socket, a rail carried by the plate, a rail clamp wedgingly assembled between said rail and said abutment and a fastening member supported non-rotatably in the

socket and arranged to detachably secure the rail clamp to the plate.

10. In combination, a tie plate for tracks comprising a plate adapted to carry a track rail and formed to provide an abutment for a track rail clamp, an integral perforated boss formed in said plate in spaced relation with said abutment and a fastening member mounted non-rotatably in said perforation in position to engage and secure a rail clamp to the plate. 75

11. In combination, a tie plate for tracks comprising a plate adapted to carry a track rail and formed to provide an abutment for a track rail clamp, a track rail supported by the 80 plate and bearing against said abutment and the track rail, a fastening member comprising a headed bolt carried by the tie plate and having a portion co-operating with the rail clamp for detachably holding same in position on the tie plate and co-operating means formed in the bolt and tie plate for normally preventing relative rotation there between, said plate having a perforation through which the shank of the bolt may be assembled, 85 said plate being also provided with an embossment in its underside for receiving the head of the bolt above the lower surface of the plate. 90

12. The combination of a tie plate for 95 tracks comprising a plate adapted to support a track rail and formed to provide an abutment for a rail clamp, a track rail carried on the plate and a rail clamp engaging said abutment and said track rail, said plate having a perforated embossment and a fastening member comprising a headed bolt having a shank extending through said perforation and having detachable connection with said rail clamp to hold same in place on the plate, 100 the head of said bolt extending in the depression of the embossment on the underside of the plate whereby the head of the bolt is maintained above the lower plane of the plate 105 in position preventing laceration of the tie 110 on which the plate may be mounted.

13. In combination, a tie plate for tracks comprising a plate adapted to carry a track rail and formed to provide an abutment for a rail clamp, said tie plate having an integral 115 perforated embossment formed therein in spaced relation with respect to said abutment, a fastening member mounted in said perforation in position to engage and secure a rail clamp to the plate, said perforation and fastening member providing co-operating means preventing relative rotation therebetween. 120

In witness whereof, I have hereunto subscribed my name.

BENEDICT T. GIBBS, JR. 125
